UNITED STATES PATENT OFFICE.

JULIUS M. GRENZFELDER, OF ST. LOUIS, MISSOURI.

TRUSS AND TRUSS-FRAME.

1,160,402.

Specification of Letters Patent.

Patented Nov. 16, 1915.

Application filed July 13, 1914. Serial No. 850,679.

To all whom it may concern:

Be it known that I, JULIUS M. GRENZFELDER, a citizen of the United States, residing in the city of St. Louis, in the State 5 of Missouri, have invented new and useful Improvements in Trusses and Truss-Frames, of which the following is a specification, reference being had to the accompanying drawings.

10 My invention and improvements relates to that class of surgical appliances known as trusses and supporters for the treatment of rupture in its different forms and location, abdominal ailments or any other bodily disease or condition wherein a supporting truss or frame, equipped with proper auxiliary pads where required, may be of service in alleviating pain or otherwise promoting the treatment of the ailment. For the purposes 15 above stated there are now in use several very excellent forms of trusses and supporters, all of which however, have certain objections, which it is the purpose and object of my improvements to overcome.

20 One object accordingly, of my invention is to provide a truss frame which is light, strong and so constructed as to readily conform and adjust itself to the shape and contour of the body of the wearer, without requiring special bending for that purpose.

25 Another object is to provide a truss frame which will not curl or bend out of shape along horizontal lines but will maintain its rigidity at all times.

30 Another object of my invention is to provide a truss frame construction, whereby the truss when so constructed, may be readily and instantly adjusted by the patient himself, without requiring the service of a physician or surgeon.

35 Still another object is the providing of a truss which may be readily lengthened or shortened at will, and one whereby the required pressure may be easily adjusted to 40 any point upon the body, at will.

I attain these and other objects by the mechanism and arrangements illustrated in the accompanying drawings, in which—

45 Figure I shows a truss frame, equipped with pad and all complete except the covering. Fig. II shows a truss, constructed in accordance with my improved method, properly adjusted in place upon a human body,

55 with a pad suspended from the front thereof and bearing upon a point at the left of the abdomen. Fig. III shows a side view of the same truss upon the body. Fig. IV is a detail sketch showing method of assembling and joining the several links composing a complete truss or supporter as above referred to. Fig. V shows the preferred method of construction of the pad and center, and Fig. VI shows another form of construction of the links making up a truss or supporter.

60 65 Similar figures refer to similar parts throughout the several views.

Referring now more particularly to the drawings, in Fig. I the figures 11, 1, 7, 5, 9, 3, 13, 14, 10, 6, 8, 2 and 12, exhibit the general shape in the preferred form of construction, of the frontal portion of one of my trusses, and it will be noted that the contour is such, through the upward bending of the frame at the points 8 and 10, as 70 to form the arches at the points 2 and 4, which comfortably adjust over the hips 62 and 63 (Fig. II), and at the same time a depressed central connecting portion 8 to 10, upon and along which at any point desired may be clamped the pad 47 for affording pressure upon any desired portion of the abdomen. It will be noted that the extremities of said frontal piece spread and diverge, as at 11, 12 and 13, 14, and that 75 from said extremities depend a series of links 15, 16, 17 and 18, 19, 20, connected together by means of the tubular collars 48, 49, 50 and 51, 52, 53, and it will also be noted that the upper and lower sides of said 80 links are not exactly parallel, but gradually converge, so that progressing from front to back, each successive link is slightly smaller 85 in size than its predecessor. To the last and smallest link on each side, as at 17 and 20, are connected the ordinary leather or canvas straps 23 and 32, the strap 23 being punctured along a medial line with the holes 24, 25, 26, 27 and the strap 32 being equipped 90 with the buckle 33, whereby ready means 95 are afforded for fastening the apparatus upon the body. The said frontal piece represented by the figures 11, 1, 7, 5, etc., is preferably constructed of spring steel wire, or stamped from spring steel in sheet form, 100 but may be constructed of and from any

105

other material which will afford the proper strength and resiliency necessary for the purposes of the apparatus. It will be noted that the pad 47 may be slid along and upon the central portion between the points 8 and 10, and clamped securely in place at any desired point. In Fig. I the naked truss frame is shown, wherein resides the gist of my invention. Said frame of course may be covered in any suitable manner and with any suitable material, for the purpose of rendering same more comfortable to the wearer, or for other purpose. The merits of this form of construction of truss and frame are such that whereas, it is necessary in the ordinary forms of truss to bend and shape and otherwise adapt the truss to the individual wearer, a truss constructed in accordance with my invention and the principles herein outlined automatically adjusts itself and conforms itself to the form of the individual wearer, while at the same time the spring frontal portion aforesaid yields and affords the requisite degree of pressure and tension upon the desired spot upon the body, through the medium of the pad 47. It will also be noted that a truss so constructed of said series of links, while perfectly flexible and yielding to motion and pressure within the plane of the circle formed by joining the two free ends of the truss, is yet absolutely rigid and unyielding to forces bearing upon the truss along vertical lines, and which forces cause an ordinary leather or canvas truss or belt to weaken along medial lines so as to bend, warp and curl out of shape. It will further be noted that this form of construction of truss, while affording a wide bearing between the points 11 and 12 and 13 and 14, whereby a strong leverage may be brought to bear upon the pad 47, yet permits of the gradual tapering of the truss through its successive links toward either end for the purpose of connecting with the straps 28 and 32. This form of construction therefore, affords a truss at once light and very strong, great flexibility where such quality is desirable and great rigidity where this is desirable; a truss whose automatic and self adjusting features enable any one, without the service of a physician, to instantly adjust the apparatus upon his own person; a truss cheap to make and durable in wear; a truss whereby pad pressure may be readily brought to bear upon any portion of the body without any special bending or shaping of the same.

In Figs. II and III are shown the method of applying and fastening the trusses and supporters upon the body, showing how my construction affords perfect lateral flexibility and vertical rigidity. In the actual use of the truss for instance, shown in Fig. II, the apparatus is placed around the ab-

domen, so that the arches at 2 and 4 come immediately over the hips 62 and 63, allowing freedom of movement for the legs, while upon the central shaft 8 to 10 is suspended the pad 47, which by means of the clamp 70 67 may be adjusted and firmly secured at any desired place for pressure upon any desired portion of the abdomen. The straps 23 and 32 are then buckled at the back, whereby, through the resiliency of the said frontal shaft, the desired pressure is brought to bear upon the body through the pad 47. It will be readily seen that this same form of construction by link formation, may be applied and used for the making of all 80 kinds of trusses, supporters, belts, braces, bandages, etc., and while I have here described a particular construction both of the complete truss or supporter and of the individual links making up the same, I reserve the right to make any minor changes or modifications in the same or in any of the elements thereof, which do not depart from the spirit of my invention. For instance, in Fig. VI is shown another form 90 of construction for the links, showing links stamped from sheet metal as at 77, 81 and 85, each bearing at one side the slots 78, 82 and 88 and at the other side the tongues 79, 80, and the method of joining the link 81 95 to the link 85 by inserting the tongues on link 81 through the slot on link 85 and bending said tongues backward as shown at 83 and 84. Again, Fig. IV shows in detail a method of construction and assembling of 100 the wire links, cross sectional views of the tubular connecting collars being shown at 51, 52 and 53, with method of bending the wire links into approximately rectangular form as shown at 70, 75, 76 and 68, and method of inserting and hinging the ends 69 and 71 of each successive link into the open ends of the tubular collar of the preceding link as at 72, so as to form the perfectly hinged link as at 18. 110

In Fig. V is shown a method of construction of a pad and center, wherein 47 represents the pad and 66 the center, which center may be either made integrally with the pad, or affixed rigidly thereto, or may consist of a ball 66, —revolvably mounted within its socket 89 formed in the pad 47. The advantage of the revolving center being that it more readily moves across the body and falls into place easier than does the rigid center, and at the same time tends to massage the afflicted portion of the body on which it rests, which in itself promotes the treatment. 115

Having thus described my invention, what 125 I claim to be new and patentable is:
The combination of a truss frame composed of a resilient, bow-like, pad-carrying frontal piece formed with lowered center, widened extremities and arches to fit over 130

the hips, and supporting chains dependent from each extremity of said frontal piece, said chains being formed of trapezoidal links hinged together from their parallel sides 5 with the longer parallel side of each successive link conforming to the shorter side of the preceding link, so that the whole chain-

frame tapers gradually toward the back each side of said frontal piece, with a pad adjustably mounted upon said frontal piece. 10

JULIUS M. GRENZFELDER.
